 The George W. Borg Corporation, Chicago, Ill.,
 a corporation of Delaware

Application October 8, 1945, Serial No. 620,975

8 Claims. (Cl. 250—36)

1

This application is a continuation in part of my prior application Serial Number 477,237, filed February 26, 1943 and now Patent Number 2,410,389.

The present invention relates in general to frequency conversion apparatus, and more in particular to so-called frequency dividers which are employed to obtain a desired low frequency output from a high frequency input. The object of the invention is to produce a new and improved apparatus of this character.

The invention is useful, for example, in generating standard frequency alternating current for running the constant speed motor of a watch timing device. In such a generator a source of constant frequency alternating current is required. A crystal oscillator has a substantially constant frequency and accordingly is very desirable for this purpose, but the frequency is far too high for use in running a motor. However, by the use of a suitable frequency divider the high crystal oscillator frequency (in the neighborhood of 90,000 cycles per second) can be reduced to a sub-multiple frequency of 100 cycles per second or some other desired low frequency, and by suitable amplification of the low frequency output of the frequency divider the required low frequency current for running the motor may be obtained.

Apparatus of the foregoing character, comprising a crystal oscillator, frequency divider, and amplifier, may be referred to as a constant frequency generator, and has been used extensively in connection with watch timing apparatus. In this known generator the frequency divider comprises a plurality of multivibrator stages connected in tandem and each operating at a frequency which is a sub-multiple of the frequency at the preceding stage.

A frequency divider using multivibrators operates very satisfactorily. At each stage, however, it requires two tubes or the equivalent, and since the rate of division is rather low (rarely exceeding 5 or 6), a considerable number of stages is required. For these reasons the cost of a standard frequency generator using multivibrators is rather high.

A specific object of the present invention, therefore, is a frequency divider using single tube oscillators instead of multivibrators. Another object is a frequency divider having a larger division at each stage than has been considered practicable in frequency dividers using multivibrators.

A well known single tube oscillator is the so-called Hartley oscillator, employing a tuned plate

5 circuit and a grid circuit inductively coupled thereto. The standard Hartley oscillator, however, is entirely unsuited for use as a frequency divider, for reasons which need not be gone into in detail. For one thing, the standard Hartley oscillator is not susceptible to reliable control at a sub-multiple frequency by alternating currents derived from a crystal oscillator. Another difficulty arises from the fact that if it is attempted to control a Hartley oscillator at a sub-multiple frequency from a similar oscillator the controlled oscillator tends to operate as an amplifier at the control frequency.

In this situation, I have discovered that with 15 suitable coupling arrangements which I have also devised a somewhat different single tube oscillator can be made to operate very satisfactorily as a frequency divider. The new oscillator differs from the standard Hartley oscillator in several respects, as will be explained fully hereinafter in 20 describing its construction and operation. One feature which is important and which may be mentioned at this time is the wave shape of the oscillator grid voltage. I have discovered that for 25 satisfactory operation the positive half of the wave must be decidedly limited in amplitude, with a characteristic flat top.

Another feature of the invention relates to the 30 solution of the problem involved in causing an oscillator to divide by an odd or an even number; and to the discovery I have made that for the best results an oscillator designed for odd division has to be different from an oscillator designed for even division. The first step in the solution 35 of this problem was the discovery that excellent results could be obtained by inserting a condenser and leak resistor in the grid circuit of an oscillator intended for odd division and by omitting these parts in the case of an oscillator intended 40 for even division. Further investigation in the course of which a larger number of different circuits were tried resulted in the discovery that the ratio of plate to grid coupling in the oscillator transformer is of importance in this connection.

45 Pursuing this clue, and after extensive tests of different transformer ratios, I have found that in an oscillator for odd division the ratio of the number of turns in the plate winding of the transformer to the number of turns in the grid winding should be about 3 to 2, or even about 1 to 1, whereas in an oscillator for even division the ratio should be at least twice as great and preferably about 3.5 to 1 or 4 to 1. Except for the difference in the transformer windings the oscillators for odd and even division may be the same.

The invention and the various features thereof will be fully described hereinafter, reference being had to the accompanying drawings, in which—

Fig. 1 is a diagrammatic circuit drawing of a standard frequency generator embodying the invention;

Fig. 2 is a similar circuit showing a modification in which the oscillators have different transformer ratios to facilitate odd or even division as the case may be; and

Fig. 3 is a chart or graph showing the result of tests made on a 90 cycle oscillator such as is shown in Fig. 2.

Referring to Fig. 1, the complete equipment therein shown is a standard frequency generator which may be used, for example, to supply alternating current for running a small motor at constant speed. The principal component parts of the generator are a crystal oscillator, a three-stage frequency divider, and a power amplifier. The crystal oscillator and power amplifier are of known construction. The invention relates to the combination of these elements with the frequency divider and more in particular to the frequency divider per se, as previously indicated.

The frequency of the crystal oscillator is assumed to be 90,000 cycles per second, as indicated in the drawing. The three oscillators which comprise the three-stage frequency divider divide, respectively, by 10, 10 and 9, and oscillate at frequencies of 9,000, 900 and 100 cycles per second, respectively. This arrangement, giving an output frequency of 100 cycles per second, is satisfactory for the intended purpose, although it will be understood that the invention is not limited to the employment of any specific frequencies. By selecting a different oscillator frequency, or by adjusting one or more of the oscillators at the frequency divider to divide differently, or both, various other output frequencies may be obtained.

Describing the equipment more in detail, the reference character 10 indicates a suitable space discharge device, which may be a type 6J7 pentode. This tube functions as a combined oscillator and amplifier tube. The control grid and the screen grid are coupled to the crystal, as shown, by means of condensers. The screen grid functions as the plate or anode in this circuit, being supplied with anode potential through the resistor 11, which may have a value of 500 M ohms. The control grid is connected to ground through the resistor 19, which may have a value of one megohm. There is a reactance coil 20, value about 20 millihenrys, which is connected in series with the crystal 16, and the oscillator is tuned to the exact frequency by means of the condenser 18. The control and screen grids function also in the amplifier. The suppressor grid is connected to the cathode as shown, and the plate is connected to the plus B lead through the resistor 21, which may have a value of 500 M ohms.

The first oscillator stage of the frequency divider comprises a space discharge device 11, which may be a type 6J5 triode. Explaining the oscillator circuits briefly, the cathode is grounded, and the plate is connected to the plus B lead through the resistor 25, the value of which may be 50 M ohms. There is a tuned circuit comprising the inductance 29 and the condenser 28 which is connected between the plate and ground by means of the condenser 27. This condenser preferably has a value of .001 MF and is shunted by the 100 M ohm resistor 26. The inductance 29 is

one winding of a transformer the other winding 30 of which is connected to the control grid of the tube through the 10 M ohm resistor 24. The ratio of primary turns to secondary turns is preferably about 4 to 1, as indicated.

In order to control the oscillator 11 from the preceding stage the control grid of tube 11 is coupled to the plate circuit of tube 10 by means of the resistor 23 and the condenser 22. The resistor 23 preferably has a value of 150 M ohms, while the capacity of the condenser 22 may be 100 MMF.

The second oscillator stage of the frequency divider comprises the space discharge device 12, which may also be a type 6J5 triode. This oscillator is similar to the first stage oscillator except for different values of some of the circuit elements. Thus the coupling condenser 31 preferably has a value of .01 mf. The ratio of turns in transformer winding 32 to the turns in the secondary winding 33 is 2 to 1. The resistors 34 and 35 preferably have values of 50 M ohms and one megohm, respectively.

The third oscillator stage of the frequency divider comprises the space discharge device 13, which may be another type 6J5 triode. The coupling condenser 40 preferably has a value of .1 mf. The turn ratio between the transformer windings 41 and 42 is 2 to 1, and the values of the resistors 44 and 45 are preferably 50 M ohms and 500 M ohms, respectively. There is a condenser 46 (capacity .05 mf.) in the grid circuit, shunted by the leak resistor 47 which preferably has a value of 100 M ohms.

The power amplifier comprises the tubes 14 and 15, which may be of any suitable type, and includes the output transformer 50. The conductors 51 and 52 constitute the output circuit, which may lead to a small synchronous motor.

The amplifier is of the push-pull type and the grids of the tubes are controlled from the third oscillator stage of the frequency divider, as indicated in the drawing. In this connection it will be noted that the oscillator transformer has a third winding 43. Windings 42 and 43 together have the same number of turns as winding 41, whereby equal and opposite voltages to ground are available for application to the grids of tubes 14 and 15. The resistor 55 is the usual cathode biasing resistor.

It will be understood that if the frequency divider has an even number of stages, four for example, two type 6F8 double triodes may be used instead of four type 6J5 triodes.

The apparatus having been described, the operation of the complete standard frequency generator will now be explained.

The operation of the crystal oscillator and amplifier stage 10 is well known and need not be described in detail. Suffice it to say that by the operation of the crystal oscillator section of the tube 10 fluctuating currents having a frequency of 90,000 cycles per second are set up in the plate circuit of the amplifier section of the tube, whereby fluctuating voltages of the same frequency are made available at the plate for application over the control circuit to the grid of the tube 11 of the first oscillator stage of the frequency divider. The crystal oscillator may be tuned to the exact frequency of 90,000 cycles per second by means of the condenser 18.

The first stage oscillator 11 of the frequency divider has a frequency of 9,000 cycles per second and is driven or controlled at exactly that frequency by voltages transmitted from the plate

circuit of tube 10 by way of the condenser 22 and resistor 23 to the grid of tube 11.

The second stage oscillator 12 of the frequency divider oscillates at a frequency of 900 cycles per second. It is controlled at exactly that frequency by voltages developed across the tuned circuit 28-29 of the first stage oscillator and transmitted to the grid of tube 12 through the resistor 35.

The third stage oscillator 13 of the frequency divider oscillates at a frequency of 100 cycles per second and is controlled at that frequency by voltages developed across the tuned circuit 36-32 of the second stage oscillator and transmitted by way of resistor 45 and grid condenser 46 to the grid of tube 13.

The push-pull amplifier 14-15 amplifies the 100 cycle output of the third stage oscillator, said output comprising equal and opposite voltages to ground which are developed in the windings 41 and windings 42 and 43 of the oscillator transformer. These voltages control the operation of the amplifier in known manner, with the result that alternating current having a frequency of 100 cycles per second is transmitted over the output circuit 51-52.

The foregoing is a more or less general description of the operation. Attention will now be directed more particularly to the features of the oscillators in the frequency divider hereinbefore mentioned and other features which are desirable or essential to satisfactory performance.

The tuning of the oscillators may first be considered. The oscillator 12, for example, oscillates under control at a frequency of 900 cycles per second. It may be tuned to that frequency, but is preferably tuned to a somewhat lower frequency. The tuning is accomplished by selecting a condenser 36 of the proper capacity and by adding a small trimmer condenser as indicated, if required. The frequency to which the oscillator should be tuned for the best results is determined by ascertaining the upper and lower limits of the natural or uncontrolled frequency which the oscillator may have and be susceptible to control at 900 cycles per second. A frequency is then selected which is higher than the lower frequency limit by approximately one-third of the total range between the upper and lower limits, and the oscillator is then tuned to this frequency.

To illustrate the foregoing, I have found that if other factors are properly taken care of, as will be explained presently, the oscillator 12 may have a natural frequency ranging from the lower limit of about 820 cycles per second to the upper limit of about 915 cycles per second and still be susceptible to control at 900 cycles per second from the preceding 9,000-cycle oscillator. This is a range of 95 cycles. One-third of 95 cycles is approximately 32 cycles, which when added to 820 cycles gives 852 cycles per second as the proper frequency to which the oscillator should be tuned.

The reason for tuning to the low side of the range is two-fold. The operative natural frequency range extends farther below the operating frequency of 900 cycles per second than it does above it, and the changes which may be expected to occur in time, such as changes in condenser capacity or variations in resistance of the resistors, tend to increase the natural frequency of the oscillator.

The condenser 31 is the coupling condenser through which power is delivered from the plate

circuit of oscillator 12 to the tuned circuit comprising condenser 36 and inductance 32. Whereas a large condenser on the order of 2 mf. in capacity is generally used at this point, I have found it desirable to use a condenser of much lower capacity in order to limit the amount of power transferred. Otherwise too high a voltage appears across the tuned circuit, and it is very difficult to properly proportion the other circuit elements. It will be noted that the condensers such as 31 have different capacity values depending on the frequency of the oscillators to which they belong. Condenser 31 has a capacity of .91 mf., condenser 27 has a capacity of .001 mf., while condenser 40 has a capacity of .1 mf. These values are not critical, but it is important to use such values that the described limiting effect is secured.

It has been found that when the condenser 31, for example, is made of low enough capacity to substantially limit the power transferred to the associated tuned circuit it has a considerable effect on the tuning of the tuned circuit, and any change which might occur in the capacity of the condenser would change the oscillator frequency appreciably. It is desirable to eliminate as many changeable factors as possible, and accordingly the condenser 31 is shunted by the high resistance resistor 37. When this shunt is used the capacity of condenser 31 can change by as much as 20% without causing failure of the oscillator to divide properly. A similar shunt resistance 26 is connected around the condenser 27 at the oscillator 11.

The tuned circuits at the several oscillators should each have a rather high inductance to capacity ratio, and for this purpose iron cores are used in the oscillator transformers.

The fact that the oscillator grid voltage should have a wave shape characterized by a low amplitude flat-topped positive half wave has previously been mentioned. At the oscillator 12 the required wave shape is secured by means of the high resistance 34 in the grid circuit. When the grid swings positive it starts to draw current, but the resistance 34 is so high relative to the internal resistance of the tube (cathode to grid) that the major part of the total voltage in the grid circuit is developed across the resistor 34 and the potential of the grid relative to the cathode is limited to a low value. Similar resistors are used in the grid circuits of the other oscillators in the frequency divider. This is an important feature, since it is impossible to properly control the oscillators at the desired submultiple frequencies unless the resistors are present in the grid circuits.

The ratio of the control voltage to the oscillator grid voltage is also of paramount importance. Considering the oscillator 12 again, the grid voltage is the voltage generated in the secondary winding 33 due to its coupling with the primary winding 32. It is the coupling between these two windings, one in the plate circuit and the other in the grid circuit, that makes the tube oscillate. By the term "control voltage" I mean the voltage that is transmitted from the preceding stage and applied to the grid of tube 12 to cause it to oscillate at exactly the desired frequency. This voltage is transmitted over a circuit to ground which includes the resistor 35, the resistor 34 and the winding 33, the latter having such a low resistance that it may be neglected. The grid of the tube 12 being connected to the junction of resistors 35 and 34, these resistors operate as a volt-

age divider or potentiometer and the ratio of resistance 35 to resistance 34 determines what proportion of the total voltage available will be effective at the grid of the tube.

Now I have found that for the best results the control voltage should be approximately 15% of the grid voltage. The desired ratio is secured by a proper proportioning of the factors which affect it, but mainly by selecting a resistor 35 having the proper resistance value.

In stating that the best results are secured when the control voltage is 15% of the grid voltage, I mean that with this ratio of control voltage to grid voltage the oscillator may be tuned to any frequency within a maximum frequency range and still be susceptible to control at the desired frequency of 900 cycles per second, and that if the ratio is changed substantially in either direction the frequency range is correspondingly narrowed. This may be illustrated by the results of tests on the 900-cycle oscillator 12. It was previously mentioned that this oscillator may have a natural or uncontrolled frequency ranging from 820 cycles per second to 915 cycles per second, but it will be understood now that it has this large frequency range only when the control voltage bears the optimum relation to the grid voltage. I have found that if the control voltage is raised to 30% of the grid voltage the natural frequency range within which the oscillator may be tuned becomes approximately 825 cycles to 880 cycles, while if the control voltage is decreased to 7 1/2% of the grid voltage the frequency range becomes approximately 870 cycles to 920 cycles. These values show a considerable narrowing of the range and indicate the importance of maintaining the ratio of control voltage to grid voltage within fairly close limits and as near to the best ratio as is practicable. The same ratio is used at all the oscillators of the frequency divider.

Attention has already been directed to the fact that a condenser is used in the grid circuit at the oscillator 13, which divides by 9. I have discovered that in the case of an oscillator which divides by an odd number the insertion of a condenser of the proper capacity in the grid circuit approximately doubles the natural frequency range within which the oscillator may be tuned. In the case of an oscillator which divides by an even number, however, the use of a grid condenser is of no avail and actually decreases the range. Accordingly, at any stage where odd division is required the grid condenser is used, but is omitted at other stages.

Referring now to Fig. 2, the standard frequency generator therein shown comprises a crystal oscillator and a four-stage frequency divider. The power amplifier which will usually be required has been omitted but it will be understood that a suitable amplifier can be driven from the output conductor 115 at the last stage of the frequency divider, or if desired a push-pull amplifier can be coupled to the final oscillator by the circuit arrangement shown in Fig. 1.

As indicated in the drawing, the crystal oscillator operates at a frequency of 81,000 cycles per second. The four oscillators which form the four-stage frequency divider operate at frequencies of 16,200, 2,700, 450, and 90 cycles per second respectively, dividing by 5, 6, 6, and 5 respectively. As in the case of the frequency divider shown in Fig. 1, practically any desired output frequency may be obtained by selecting a different oscillator frequency, or by changing the rate of division

at one or more stages, or by a combination of these methods.

The crystal oscillator comprises the crystal 101 and the space discharge device 110, which may be a type 6J7 pentode operating as a combined oscillator and amplifier tube. The circuit arrangement is generally similar to the circuit of the crystal oscillator shown in Fig. 1 and will not need to be described in detail.

10 The first oscillator stage of the frequency divider comprises a space discharge device 111, which may be a type 6J5 tube, and the associated circuit elements shown. The cathode is grounded, and the anode is connected to the plus B lead through the resistor 116, which may have a value of 50 M ohms. The tuned circuit comprising the inductance 118 and the condenser 121 is connected between the anode and ground by means of the condenser 117, which preferably has a 15 value of about .0015 mf. This condenser may be shunted by a resistor if desired for reasons explained in connection with Fig. 1, but the shunt is not strictly necessary and in the circuit of Fig. 2 it has been omitted. The inductance 118 is one winding of a transformer the other winding 119 of which is connected to the control grid of the tube through the resistor 123, which may be 75 M ohms. The ratio of the number of turns in winding 118 to the number of turns in winding 119 may be 3 to 2, as indicated in the drawing, and should not differ greatly from this ratio, as will be explained more fully hereinafter.

15 The oscillator 111 is coupled to the crystal oscillator by means of the condenser 124 and the resistor 125. The condenser may have a capacity of 100 mmf. while the resistor may be 500 M ohms.

The second oscillator stage of the frequency divider comprises the space discharge device 112, which may be another 6J5 tube, together with the 20 other circuit elements shown. The essential difference between the second stage oscillator 112 and the first stage oscillator 111 resides in the different transformer ratios which are employed. In the oscillator 111, which divides by the odd integer 5, a 3 to 2 ratio is used, as already explained, whereas in the oscillator 112, which divides by the even integer 6, a ratio more than twice as great is used. Excellent results have been obtained when the ratio of the number of 25 turns in the plate winding 127 to the number of turns in the grid winding 128 is 3.5 to 1. The ratio may be somewhat lower and may be as high as 4 to 1.

30 It will be understood of course that the coupling condenser 126 should have a higher capacity than the corresponding condenser 117 in the first stage, due to the lower operating frequency of the second stage. Condenser 126 may have, for example, a capacity of .005 mf. The control resistor 130 and the grid resistor 129 may be the same as the corresponding resistors in the first stage, that is, these resistors may be 500 M ohms and 75 M ohms, respectively. It is found, however, that somewhat better results are obtained if resistors of other values are used, the values being selected so as to compensate roughly for the lower grid voltage which results from the 3.5 to 1 transformer ratio, and thus avoid disturbing to any great extent the best ratio of the control voltage to the grid voltage. It was explained in connection with Fig. 1 that the control voltage should be about 15% of the grid voltage, although the relation is not critical. In view of the foregoing it is preferable to use at each even division stage, 35 control and grid resistors so selected that the dif-

ference between their values is considerably greater than the difference between the values of the corresponding resistors at the odd stages. Excellent results have been obtained with a control resistor 130 of 650 M ohms and a grid resistor 129 of 50 M ohms.

The third stage oscillator 113 may be the same as the second stage oscillator 112, except that it is tuned to a lower frequency. The coupling condenser 131 may have a capacity of .025 mf.

The fourth stage oscillator 114 divides by 5 and accordingly is similar to the first stage oscillator 111 except that it is tuned to a different operating frequency. A coupling condenser 132 having a capacity of .10 mf. may be used.

While four ordinary triodes have been shown in the drawing, it will be understood that type 6SN7 tubes or the equivalent may be used. By using these double triodes the number of tubes required for a four-stage frequency divider is reduced to two tubes.

The operation will be readily understood from the explanation previously given in connection with Fig. 1. The crystal oscillator operates at a frequency of 81,000 cycles per second and drives the first stage oscillator 111 of the frequency divider, which divides by 5 and operates at a frequency of 16,200 cycles per second. The oscillator 111 drives the second stage oscillator 112 which divides by 6 and operates at a frequency of 2,700 cycles per second. The third stage oscillator 113, dividing by 6 and operating at a frequency of 450 cycles per second, is driven by the oscillator 112 and in turn drives the final stage oscillator 114 which divides by 5 and operates at a frequency of 90 cycles per second. The output conductor 115 may be used to control any suitable power amplifier, as previously mentioned.

Reference may now be made to Fig. 3, which shows the selective action of two different transformer ratios as affecting odd and even division. This chart or graph, constructed from actual test of a 90 cycle oscillator, shows that with a transformer ratio of 3 to 2 the oscillator strongly favors an odd division, while with a transformer ratio of 3.5 to 1 the oscillator shows a strong tendency to operate at a frequency which is the result of an even division.

The test was made by driving an oscillator such as oscillator 114, Fig. 2, from a variable frequency oscillator adapted to supply driving potentials having about the same voltage as the control voltage obtained from oscillator 113 and having a variable frequency ranging from about 200 cycles per second up to about 1,000 cycles per second.

The heavy horizontal lines on the chart which are labeled "Odd—3:2" at the right show the frequency ranges for odd and even division when the oscillator is designed for odd division by using a transformer with a 3 to 2 ratio.

The heavy horizontal lines which are labeled "Even—3.5:1" at the right show the corresponding frequency ranges when the oscillator is designed for even division by using a transformer with a 3.5 to 1 ratio.

In the oscillator intended for odd division the control and grid resistors such as 133 and 134 preferably have values of 500 M ohms and 75 M ohms, respectively, while in the even division oscillator the corresponding resistors preferably have values of 650 M ohms and 50 M ohms, as previously explained. It may be stated, however, that the same selective action is observed if the control and grid resistors are the same in both

oscillators although the discrimination is not so pronounced.

In making a test on the oscillator designed for odd division, for example, the variable frequency driving oscillator is adjusted to deliver driving potentials having a low frequency such as 250 cycles per second and is connected to the oscillator to be tested. The frequency of the driving voltage is then raised gradually and at the same time the output frequency of the oscillator is compared in well-known manner with the driving or input frequency by means of a cathode ray oscilloscope so that the rate of division can be observed. Since the oscillator being tested is tuned for operation at 90 cycles per second, it will divide at a rate which will enable it to operate at a frequency most nearly approximating 90 cycles per second, and will increase its rate of division as the input frequency is raised.

Thus when the frequency of the driving voltage is 270 cycles per second the oscillator divides by 3, when the frequency of the driving voltage is 360 cycles per second the oscillator divides by 4, and so on. This is shown clearly by the digits 3, 4, 5, etc. which are associated with the heavy lines on the chart. These lines also show, by their lengths, the frequency ranges for stable operation at the different rates of division. For division by 5, for example, the oscillator has a range of input or control voltages of over 100 cycles per second. The range for division by 7 is even greater. The range for division by 6, on the other hand, is less than 50 cycles per second and for division by 4 is still less.

At this point it should be explained that an oscillator such as disclosed herein, when oscillating under control at a sub-multiple frequency, displays a certain tendency to maintain its rate of division notwithstanding a change in input frequency to a value outside the stable range corresponding to such rate of division. This tendency accounts for the fact that the heavy range lines do not join each other but are separated by spaces corresponding to frequency ranges in which the oscillator is unstable or will give either an odd or even division. For example, if the input voltage is 400 cycles per second the oscillator will divide by 5 and it will continue to divide by 5 as the frequency of the input voltage is increased until the frequency reaches the lower limit of the division by 6 range, whereupon the oscillator will start to divide by 6. If the frequency of the control voltage is now decreased the oscillator does not at once start to divide by 5 again but continues to divide by 6 until the control frequency is lowered to the upper limit of the division by 5 range. The limits of the stable ranges are determined by raising the control frequency from a minimum to a maximum value and then lowering it to the minimum value and by noting the frequencies at which the oscillator changes its rate of division.

Attention may now be directed to the upper set of range lines, which were determined by testing a 90 cycle oscillator in which the plate to grid transformer coupling ratio is 3.5 to 1. It will be seen that for division by 6 the oscillator has a range of control voltages of more than 125 cycles. It also has a very wide range for division by 4. For division by 5, however, the range is only about 50 cycles, and for division by 7 the range is only a little more than 25 cycles.

Comparison of the two sets of range lines demonstrates clearly that an oscillator in which the coupling ratio is 3 to 2 favors an odd division,

11

whereas an oscillator with a 3.5 to 1 coupling ratio favors an even division. It will be apparent therefore that a frequency divider in which the oscillator stages for odd division have transformers with a coupling ratio of about 3 to 2 and in which the oscillator stages for even division have a coupling ratio of about 3.5 to 1 is inherently more stable, that is, less susceptible to trouble due to changes in tuning occurring over a period of time, than a frequency divider in which the coupling ratios at the odd and even stages are the same.

From what has been said already it will be understood that the coupling ratios to be used are not critical. An oscillator having a transformer with a coupling ratio of 3.5 to 1 (best ratio for even division) will divide by 5 or other odd integers but prefers to divide by an even integer. As the coupling ratio is changed to lower ratios such as 3 to 1, 2 to 1, etc. the range for odd division improves and excellent results are obtained with a ratio of 1 to 1. The best ratio appears to be about 3 to 2, in the oscillator shown herein. A similar situation exists as regards even divisions. An oscillator with a transformer having a coupling ratio of 3 to 2 (best for odd division) will divide by 6 or other even integer, but the range for even division is improved by increasing the ratio. The maximum improvement appears to result with a ratio of 3.5 to 1, although 4 to 1 gives excellent results also.

The fact that an oscillator having a coupling ratio of 3 to 2 favors odd division which an oscillator having a coupling ratio of 3.5 to 1 favors even division appears to indicate that for odd division an oscillator requires a higher grid voltage than for even division. As referred to here the grid voltage is the voltage applied to the grid of oscillator 111, for example, through the resistor 123 by the oscillator transformer comprising windings 118 and 119. It will be obvious that a higher voltage will be developed in the grid circuit with a transformer ratio of 3 to 2 than with a transformer ratio of 3.5 to 1. Tests have been made therefore to see if equivalent results could not be obtained by adjusting the value of resistor 123, using a resistor of low value for odd division and a resistor of considerably higher value for even division, but without success. Changes in the value of resistor 123 affect the value of the applied control voltage and also affect the ratio of control voltage to grid voltage, so that it is impossible to obtain any appreciable results as regards grid voltage without such an unfavorable effect on other factors that no net advantage results.

In the description certain types of tubes have been specified, and actual values have been given for various parts such as condensers and resistors, but it will be understood that this has been done merely by way of example and to assist in the understanding of certain concrete embodiments of the invention and the principles which govern their operation.

The invention having been described, that which is believed to be new and for which the protection of Letters Patent is desired will be pointed out in the appended claims.

I claim:

1. In a frequency divider, first and second oscillators each comprising a grid controlled space discharge device, a tuned plate circuit including the primary winding of a transformer, and a grid circuit including the secondary winding of such transformer, said frequency divider also in-

12

cluding a control circuit over which periodic voltages are transmitted to control the first oscillator, and a second control circuit over which periodic voltages are transmitted by the first oscillator

- 5 to control the second oscillator, the plate circuits in said oscillators being so tuned that one oscillator operates at a frequency which is an odd sub-multiple of its control frequency while the other oscillator operates at a frequency which is an even sub-multiple of its control frequency, the transformer in the oscillator which operates at the odd sub-multiple frequency having a relatively low ratio of primary to secondary turns to cause such oscillator to favor an odd division, 15 and the transformer in the oscillator which operates at the even sub-multiple frequency having a substantially greater ratio of primary to secondary turns to thereby cause such oscillator to favor an even division.

20 2. A frequency divider as claimed in claim 1, wherein the ratio of primary to secondary turns in the transformer of the oscillator which operates at the even sub-multiple frequency is at least double the ratio of the primary to secondary turns in the transformer of the other oscillator.

30 3. A frequency divider as claimed in claim 1, wherein the ratio of primary to secondary turns in the transformer of the oscillator which operates at the odd sub-multiple frequency is not less than about 1 to 1 nor more than about 2 to 1 and the ratio of primary to secondary turns in the transformer of the other oscillator is not less than about 3 to 1 nor more than about 4.5 to 1. 35 4. A frequency divider as claimed in claim 1, wherein the ratio of primary to secondary turns in the transformer of the oscillator which operates at the odd sub-multiple frequency is approximately 3 to 2 while the ratio of primary to secondary turns in the transformer of the other oscillator is approximately 3.5 to 1.

40 5. A frequency divider as claimed in claim 1, wherein at each oscillator there is a resistor included in the control circuit and another resistor in the grid circuit, the values of said resistors being so selected that the ratio of control voltage to grid voltage is approximately the same at both oscillators notwithstanding the difference in transformer ratios.

50 6. A frequency divider as claimed in claim 1, wherein each oscillator has a resistor in its control circuit and another resistor in its grid circuit, the said resistors having resistances such that they compensate at least in part for the effect which the different transformer ratios at the two oscillators has on the ratio of control voltage to grid voltage at such oscillators.

60 7. In a frequency divider, a plurality of oscillators, a space discharge device in each oscillator having cathode grid and plate elements, a tuned plate circuit in each oscillator, a grid circuit in each oscillator inductively coupled to the associated plate circuit, a control circuit for controlling the first oscillator from a high frequency source of current, and coupling circuits over which each oscillator except the first is controlled from the preceding oscillator, said plate circuits being so tuned that each of one or more of said oscillators operates at a frequency which is an odd sub-multiple of its control frequency while each of the remaining oscillators operates at a frequency which is an even sub-multiple of its control frequency, and transformers constituting the inductive couplings in said oscillators having windings so designed that the ratio

of plate to grid coupling at each oscillator which operates at an even sub-multiple frequency is at least twice the ratio of plate to grid coupling at the oscillators which operate at odd sub-multiple frequencies.

8. The method of improving the stability of an oscillator for operation as a frequency divider, said oscillator having a tuned plate circuit including the primary winding of a transformer and a grid circuit including the secondary winding of such transformer, which consists in using a low or high transformer ratio depending on whether the oscillator is to divide by an odd or even integer, the ratio of primary to secondary turns for odd division being not less than about 15

1 to 1 nor more than about 2 to 1 and the corresponding ratio for even division being not less than about 3 to 1 nor more than about 4.5 to 1.

ERNST NORRMAN.
